Application February 28, 1944, Serial No. 524,165

18 Claims. (Cl. 123—80)

1
 This invention relates to internal combustion engines and particularly to the type of engine in which a rotatable valve is provided for controlling the intake and exhaust and the firing of the combustible mixture.

The present invention is particularly applicable to an internal combustion engine of the kind in which the rotatable valve in the head, preferably although not necessarily rotatable continuously in one direction, is formed with substantially all or at least the major portion of the combustion chamber at the time of firing and is generally conical or frusto-conical in shape. The combustion chamber within the rotor or rotary valve has an opening at one end leading to the cylinder and a second opening preferably at a side thereof adapted to communicate during operation with an outlet or inlet passage, or both as the case may be, and the combustible charge within the combustion chamber is fired preferably by spark ignition.

Many difficulties are encountered in the production of a satisfactory engine of the foregoing type, one of the most serious being in connection with the lubrication of the rotary valve and in the consumption of lubricating oil. Not only is it important that proper lubrication of the valve be provided but also that the valve be constructed so as to preclude building up of excessive pressures at certain localities, due to thermal expansion of the valve, tending to destroy the oil film. It is also important that provision be made for adequate delivery of oil at localities where the greatest load occurs during operation. A further important consideration, additional to adequate lubrication and control of valve expansion, is the matter of oil consumption which in itself presents a serious problem owing to the tendency to excessive oil consumption consequent to the use of rotary valve constructions.

One of the objects of the present invention is to provide a lubricating means for a rotatable valve of the above type of engine which will be more efficient and accurate thereby improving the operation of the engine and reducing oil consumption.

A further object of the invention is to control the delivery of oil to the rotatable valve so that adequate lubrication will be available at desired localities while at the same time providing for the removal of excess oil not needed for lubrication purposes.

Still another object of the invention is to provide improved lubricating means for the valve by which lubricating oil is introduced at the high

5 pressure side of the valve bearing surface in the cylinder head and spread in a film over the bearing surfaces by wiping action while excess oil is removed by suction means so as to eliminate any material loss of oil through the valve ports especially during the suction stroke of the engine piston.

A further object of the invention is to provide an improved valve construction whereby excessive friction between the valve and cylinder head due to thermal expansion of the valve is eliminated and greater uniformity in the working clearances between the valve and head is achieved during operation.

10 Other objects of this invention will appear in the following description and appended claims, reference being had to the accompanying drawings forming a part of this specification wherein like reference characters designate corresponding parts in the several views.

15 Fig. 1 is a fragmentary sectional elevation illustrating a portion of a multi-cylinder engine embodying the present invention, this view being taken substantially through lines 1—1 of Fig. 2 looking in the direction of the arrows.

20 Fig. 2 is a horizontal section taken substantially through lines 2—2 of Fig. 1 looking in the direction of the arrows.

25 Fig. 3 is a fragmentary side elevation illustrating one of the cylinder heads.

30 Fig. 4 is an enlarged fragmentary section taken substantially through lines 4—4 of Fig. 3 looking in the direction of the arrows.

35 Fig. 5 is a fragmentary view taken substantially from lines 5—5 of Fig. 4 looking in the direction of the arrows.

40 Fig. 6 is a view similar to Fig. 4 illustrating a further embodiment of the invention.

45 Fig. 7 is a fragmentary view taken substantially from lines 7—7 of Fig. 6 looking in the direction of the arrows.

Fig. 8 is a fragmentary sectional view, in part diagrammatical, illustrating clearances between the valve and cylinder head, the same being somewhat exaggerated for the purpose of showing more clearly the features of this construction.

50 Fig. 9 is a view similar to Fig. 7 illustrating another embodiment of the invention.

Before explaining in detail the present invention it is to be understood that the invention is not limited in its application to the details of construction and arrangement of parts illustrated in the accompanying drawings, since the invention is capable of other embodiments and of being practiced or carried out in various ways.

Also it is to be understood that the phraseology or terminology employed herein is for the purpose of description and not of limitation.

In the drawings there are illustrated, by way of example, certain embodiments of the present invention as applied to an internal combustion engine of the spark ignition type which may be used for the power plant of an aircraft or motor vehicle or for other purposes, such as for marine and industrial engines. For most uses the engine is of the multi-cylinder type, although any number of cylinder units may be employed in any given engine. In the present embodiments, for the purposes of simplicity, a single cylinder unit of the engine is illustrated, it being understood that the remaining cylinders of the engine are substantially identical to the structure herein shown and described.

Referring to Fig. 1, the present engine comprises a suitable crankcase 20 carrying a cylinder 21 within which a piston 22 is mounted for reciprocation. A crankshaft (not shown) is supported in suitable bearings in the crankcase according to conventional practice and the piston is connected to the crankshaft by a connecting rod 23.

The present engine, for the purposes of illustration, is of the liquid cooled type and, accordingly, the cylinder 21 is mounted within a cylinder jacket 24, the lower end of which is brazed or otherwise secured to the crankcase 20. Between the cylinder jacket 24 and the cylinder is a liquid coolant chamber 25. The engine also comprises a cylinder head 26 having a tapped hole into which the upper end of the cylinder is threaded at 26a. The cylinder head is cast to provide a depending cylinder head jacket 27 forming a liquid coolant chamber 28 communicating with the chamber 25. The lower thickened edge of the cylinder head jacket 27 is provided with an annular groove within which is received a resilient rubber sealing ring 29 engaging the upper outer wall of the cylinder jacket 24 and placed under compression when the upper end of this jacket is forced into position, as shown, within the opening at the lower end of the cylinder head jacket. The sealing ring 29, being pressed tightly against the cylinder jacket 24, provides a liquid tight seal against leakage of the coolant from the communicating chambers 25, 28. The lower end of the cylinder 21, in the present embodiment, has a sliding fit within an opening in the crankcase 20 and the joint between the cylinder and crankcase is sealed by means of sealing rings 30.

The cylinder head 26 is formed with a valve housing 31, largely surrounded by the coolant chamber 28 and provided with a generally frusto-conical cavity 32 within which is rotatably mounted a generally frusto-conical valve 33, it being understood that the outer tapering wall of the valve corresponds generally to the shape of the juxtaposed wall of the cavity 32. The valve 33 is provided with a combustion chamber 34 having a bottom port 35, arranged in constant communication with the cylinder, and a side port 35 adapted to register in succession, during rotation of the valve, with a spark plug 37 at the spark plug location 38, an exhaust conduit 39 in the cylinder head, and an intake conduit 40 also in the cylinder head.

The piston 22 is preferably formed at its outer end with a tapered portion which projects into the combustion chamber 34 as a result of which substantially the entire combustion space, at the time of firing, is formed within the valve. In

the present embodiment, in which the valve 33 has a single port 35 in its side adapted to register in succession with the spark plug, exhaust conduit and intake conduit, the valve is rotated at one-half engine or crankshaft speed. The body of the rotary valve 33 is cored entirely around the combustion chamber 34 to provide a cooling chamber 41 containing any suitable heat transfer or conducting medium, such as metallic sodium. This chamber is sealed at its upper end by means of an expansion plug or disk 42 mounted within a bore in the projecting stem 43 of the valve.

As more particularly illustrated in Fig. 8, the outer wall of the valve 33 is relieved circumferentially at 44. This relief area preferably extends substantially entirely around the valve in the height of the side port 35. In the illustrated embodiment the height of this circumferential relief area 44 corresponds substantially to the height of the side port 35. It will be noted, as shown in Fig. 8, that this relief area increases somewhat in depth from the upper to the lower edge thereof. Also it will be noted that immediately above the upper edge of this relief area 44 the outer wall of the valve is slightly relieved at 45, but this latter relief diminishes to a point where the clearance between the valve and wall of the valve housing 31 does not exceed an ordinary running or operating clearance. Below the lower edge of the relieved area 44 the valve wall is provided with a circumferential relieved area 46 normally providing, when the valve is cold, a clearance with respect to the adjacent wall of the valve housing 31, which may exceed a normal running or operating clearance by one to one and one-half thousandths of an inch. Below the relieved area 46, which area extends continuously around the valve immediately below the side port 35, the wall of the valve is additionally relieved to provide an annular tapered or bevelled area 47 extending entirely around the valve and having a clearance at its lower edge 47a with respect to the wall of the valve housing 31, which may exceed an ordinary running or operating clearance by some four thousandths to six thousandths of an inch. The bottom surface 33a of the valve 33 has an upward inclination or taper corresponding to the taper of the top surface of the piston. This bottom inclined or tapered surface 33a of the valve terminates in an annular upwardly extending bevel or taper 48 which, as shown in Fig. 8, terminates at the lower edge 47a of the relieved area 47. It will be seen from Fig. 8 that the corner or juncture 47a of the tapered surfaces 47 and 48 is normally spaced inwardly from the upper edge of the cylinder 21 which has an annular bevel 49 at this locality. Although the above described relieved areas are preferably provided in the wall of the valve 33, it will be understood that one or more thereof may be formed in the wall 32 of the valve housing 31, and in particular the relieved area 44 may be constructed and serve the purposes in accordance with copending application Serial No. 495,260, filed July 19, 1943.

In accordance with the present invention means is provided for lubricating the bearing surfaces of the valve 33 and the valve housing 31 below the side port 35 and the annular relief 44 in the valve. Referring to Figs. 2 to 5 inclusive, the cylinder head at a point between the exhaust passage 39 and intake passage 40 and closer to the former is drilled, counterbored and tapped to provide an opening 50 into which is connected

an oil inlet pipe 51 through which lubricating oil is introduced under suitable pressure by any conventional oil pump connected to a source of supply. Extending from the inlet opening 50 is an inlet passage 50a which in turn communicates with a smaller drilled hole 52 leading to a port 53 opening through the inner wall 32 of the valve housing 31. The inlet port 53 is preferably located at a point near the lower end of the valve relief 46 but above the bevelled or tapered relief area 47 in the valve, as shown in Fig. 8. The inlet port 53 communicates with an angularly extending distributing oil groove 54 which extends upwardly in the wall 32 of the valve housing and terminates in an outlet port 55 at the end of a drilled hole 56 forming an outlet passage through the wall of the valve housing. The passage or duct 56 terminates in an enlarged tapped hole 57 into which is secured the threaded end of a coupling to which is connected a pipe 58 leading to a vacuum pump 59 or other source of suction or reduced pressure. As hereinafter described, suction induced by the pump 59 in the suction line 58—59 will withdraw excess oil entering the oil pressure groove 54 from the inlet pressure line 50—52.

In the event it is desired to supplement the passage 56 and withdraw lubricating oil from the bearing surfaces at any desired point or points circumferentially spaced from the groove 54 and port 55, additional means may be provided for this purpose as illustrated in Figs. 6 and 7 and also in Fig. 2. In this embodiment the wall of the valve housing is provided with angularly related diverging oil collector grooves 60 and 61 positioned in the height of the groove 54 and circumferentially spaced therefrom at any desired distance. A similar pair of diverging collector grooves 62 and 63 may be provided at a suitable distance from the grooves 60 and 61, and both pairs, as shown in Fig. 7, connected by a communicating groove 64 leading to a port 65 at the end of a drilled oil passage 66 communicating with the outlet opening 57. Thus, during operation of the vacuum pump 59, the suction induced in the passages 56 and 66 will cause oil to be withdrawn from the groove 54 and also the collector grooves 60—63.

In the embodiment illustrated in Fig. 9 an additional pair of collector grooves 67 and 68 are formed in the wall of the valve housing 31 above and below the oil pressure groove 54 and at a suitable distance therefrom. These grooves 67 and 68 will lie near the upper and lower edges of the relieved area 46 in the valve and may extend in substantially parallel relation as shown in Fig. 9. The collector grooves 67 and 68 communicate with drilled oil passages 69 and 70 which in turn communicate with the opening 57 so that suction induced in the line 58 will cause oil to be withdrawn from the collector grooves 67 and 68.

The valve 33 is driven at one-half engine or crankshaft speed through the medium of the projecting stem 43. Such driving mechanism for the valve is more fully shown and described in my copending application Serial No. 518,323, filed January 15, 1944. The valve is yieldingly held upwardly within the frusto-conical recess 32 in the valve housing by means of a compression spring 71 which is held under constant compression against a steel coupling disk 72 which in turn is held in place by a nut 73 engaging a bolt 74 threaded into a tapped hole in the valve stem 43. The strength of the spring 71 and the amount of preloading thereof are such that the effort ex-

erted by the spring to raise the valve within the valve housing is sufficient to substantially offset or equal the effort exerted during the suction stroke of the piston to draw the valve downwardly and away from its seat.

It will be understood that other suitable source of suction or reduced pressure than the pump 59 may be provided, and that the oil withdrawn from the collector grooves and distributing groove is returned to the oil sump or source of supply and thence returned to the bearing surfaces by the usual oil pump. The oil grooves are located at the pressure side of the valve opposite the spark plug at the locality where the greatest load comes at the time of firing, thus ensuring maintenance of an adequate oil film at the bearing surfaces most subject to friction and scoring during operation. By using a scavenge pump 59 to withdraw excess oil it is possible, and preferred, to produce a suction effort or negative pressure in the oil exhaust conduit 58 at all times somewhat in excess than the maximum suction effort or negative pressure in the cylinder during the suction stroke of the piston, especially when running idle. This enables excess oil to be returned by the pump to the oil sump rather than be drawn into the cylinder and as a consequence reduces oil consumption materially.

It will be seen that a circulation of oil to and from the valve bearing surface is maintained while at the same time control of the amount of oil actually delivered to and spread over the bearing surfaces by the wiping action of the valve is also ensured. It is desirable that the oil be delivered through duct 52 and flow into and through the distributing groove 54 under pressure, or in other words that a pressure circulation of oil through all passages and grooves be maintained, thereby preventing the accumulation or formation of carbon tending to clog the passages. It is also important that the distributing and collector grooves be connected to a source of reduced pressure or suction so as not only to maintain a circulating flow of oil but also to withdraw excess oil from the bearing surfaces. With this construction, namely, the use of a suction system to enhance circulation of oil it is possible to more accurately control the oil film, the amount of oil actually distributed over the bearing surfaces, and the consumption thereof.

It will be understood that the size and length of the oil grooves and their respective positions will be governed by the requirements and design of the particular engine, the present construction being shown for illustrative purposes.

The annular relief areas 46 and 47 are important in enabling proper lubrication to be maintained and preventing destruction or impairment of the oil film during operation. These relief areas, which may be termed expansion reliefs, offset expansion of the valve outwardly toward the valve bearing surface of the cylinder head. Preferably the relief 46 increases in depth generally proportionate to the increasing diameter of the valve so as to compensate for expansion thereof when heated during operation. The bevel relief 47 preferably increases more abruptly in depth since the greatest expansion of the valve occurs here. The construction of these reliefs, and this also applies to the annular relief 46, is such that when the valve is hottest during operation and maximum expansion thereof has occurred, the valve surfaces will have substantially a normal running or operating clearance throughout these areas with the bearing wall 32

of the cylinder head. The relief area 44 extending in the height of the valve is preferably of a depth to permit carbon to form therein, so that after continued operation this relief will be filled with carbon and provide an excellent bearing not requiring any direct lubrication with oil. This construction and the advantages thereof are more particularly described in the above mentioned copending application.

I claim:

1. In an internal combustion engine having a cylinder, a body, a rotatable valve in said body associated with said cylinder and having a combustion chamber therein, a conduit in said body for delivering oil to a groove in the valve bearing surface of the body, and a collector oil groove in said surface spaced from said first named groove and connected to a source of suction.

2. In an internal combustion engine having a cylinder, a body, a rotatable valve in said body associated with said cylinder and having a combustion chamber therein, a conduit in said body for delivering oil to a groove in the valve bearing surface of the body, a collector groove in said surface spaced from said first named groove, and means for connecting said collector groove and first named groove to a source of suction or

3. In an internal combustion engine having a cylinder, a body, a rotatable valve in said body associated with said cylinder and having a combustion chamber therein, a conduit in said body for delivering oil to a groove in the valve bearing surface of the body, and a collector oil groove in said surface spaced from said first named groove in a direction circumferentially of the valve and connected to a source of reduced pressure.

4. In an internal combustion engine having a cylinder, a body, a rotatable valve in said body associated with said cylinder and having a combustion chamber therein, a conduit in said body for delivering oil to a groove in the valve bearing surface of the body, and a collector oil groove in said surface spaced from said first named groove in a direction axially of the valve and connected to a source of reduced pressure.

5. In an internal combustion engine having a cylinder, a cylinder head, a rotatable generally frusto-conical valve in said head having a combustion chamber and a side port communicating therewith, an oil inlet conduit in said head for delivering oil to the valve, a distributing groove in the valve bearing surface of the head connected to said conduit, and conduit means connected to a source of suction or reduced pressure and communicating with said groove below said port, said groove being located below said port and above the lower edge of the valve.

6. In an internal combustion engine having a cylinder, a cylinder head, a rotatable generally frusto-conical valve in said head having a combustion chamber and a side port communicating therewith, said valve being positioned with its wider end adjacent the cylinder and having a circumferential relieved area below said port of increasing depth toward said wider end.

7. In an internal combustion engine having a cylinder, a cylinder head, a rotatable generally frusto-conical valve in said head having a combustion chamber and a side port communicating therewith, said valve being positioned with its wider end adjacent the cylinder and having a circumferential relieved area below said port of

increasing depth toward said wider end, said relieved area comprising portions of different depths, the portion of greatest depth extending around the valve proximate to the cylinder.

8. In an internal combustion engine having a cylinder, a cylinder head, a rotatable generally frusto-conical valve in said head having a combustion chamber and a side port communicating therewith, said valve having a circumferential relieved area below said port of increasing depth terminating in an annular bevel forming an expansion relief of greater depth than said relieved area.

9. In an internal combustion engine having a cylinder, a cylinder head, a rotatable generally frusto-conical valve in said head having a combustion chamber and a side port communicating therewith, said valve being positioned with its wider end adjacent the cylinder and having a circumferential relieved area below said port of increasing depth toward said wider end, and means for delivering oil to said area and also removing excess oil therefrom at a point or points below said port.

10. In an internal combustion engine having a cylinder, a cylinder head, a rotatable valve in said head associated with the cylinder, said head having a bearing surface for the valve and oil inlet and outlet conduits, and oil groove means in said surface opening toward the valve and connected to said conduits at points spaced axially and circumferentially of the valve intermediate the ends thereof.

11. In an internal combustion engine having a cylinder, a cylinder head, a rotatable valve in said head associated with the cylinder, said head having a bearing surface for the valve and oil inlet and outlet conduits, and oil groove means in said surface opening toward the valve and connected to said conduits at points spaced axially of the valve intermediate the ends thereof.

12. In an internal combustion engine having a cylinder, a body, a rotatable valve in said body associated with said cylinder, an oil groove in the body opening toward the valve for distributing oil to a circumferential area of the valve bearing surface of the head extending in the height of said groove, means for delivering oil to said groove, and means for withdrawing oil from the valve bearing surface within said area.

13. In an internal combustion engine having a cylinder, a body, a rotatable valve in said body associated with said cylinder, an oil groove in the body opening toward the valve for distributing oil to a circumferential area of the valve bearing surface of the head extending in the height of said groove, means for delivering oil to said groove, and means for withdrawing oil from the valve bearing surface at a locality spaced from said groove circumferentially of the valve.

14. In an internal combustion engine having a cylinder, a body, a rotatable valve in said body associated with said cylinder, an oil groove in the body opening toward the valve for distributing oil to a circumferential area of the valve bearing surface of the head extending in the height of said groove, means for delivering oil to said groove, and means for withdrawing oil from an intermediate region of the valve bearing surface at a point or points spaced from said groove axially of the valve.

15. In an internal combustion engine having a cylinder, a body, a rotatable valve in said body associated with said cylinder, an oil groove in the body opening toward the valve for distributing oil

to a circumferential area of the valve bearing surface of the head extending in the height of said groove, an oil inlet conduit for delivering oil to said groove, and conduit means for conveying oil from the valve surface within said area.

16. In an internal combustion engine having a cylinder, a body, a rotatable valve in said body associated with said cylinder, an oil groove in the body opening toward the valve for distributing oil to a circumferential area of the valve bearing surface of the head extending in the height of said groove, an oil inlet conduit for delivering oil to said groove, and conduit means for conveying oil from the valve surface within said area at a locality spaced from said groove circumferentially of the valve.

17. In an internal combustion engine having a cylinder, a body, a rotatable valve in said body associated with said cylinder, an oil groove in the

body opening toward the valve for distributing oil to a circumferential area of the valve bearing surface of the head extending in the height of said groove, an oil inlet conduit for delivering oil to said groove at a predetermined point, and conduit means for conveying oil from the valve bearing surface at points at opposite sides of said point of delivery.

18. In an internal combustion engine having a cylinder, a body, a rotatable valve in said body associated with said cylinder, an oil groove in the body opening toward the valve for distributing oil to a circumferential area of the valve bearing surface of the head extending in the height of said groove, means for delivering oil to said groove at a predetermined point, and means for conveying oil from the valve bearing surface at a locality between said point and the cylinder.

WALDO G. GERNANDT.
